HAIR WAVING APPARATUS

Emile J. Yven, Jackson Heights, N. Y., assignor to
 Clairol, Incorporated, Stamford, Conn., a corporation of Connecticut

Application June 3, 1939, Serial No. 277,135

13 Claims. (Cl. 132—33)

The present invention relates to hair waving apparatus, and is more particularly directed toward apparatus suitable for use in permanently waving the hair.

In the more common procedure of permanently waving the hair, the hair is passed through an opening in an insulating pad or scalp protector usually made of felt and an exposed clamp is used to secure the scalp protector to the hair so as to hold it close to the head, and prevent lotions or steam from passing through the insulating pad. The tress of hair is then wound on a mandrel and the mandrel secured in place opposite the clamp. Where electric heating is employed a moist flannel or a moist paper pad is placed about the wound hair, the same covered with foil or other impervious material, and either a heater clamp applied outside the foil, or an intrathermal heater inserted into the mandrel. Where chemical heat is employed the wetted chemical pad is applied to the wound hair, a foil or wrapper placed around the pad and a metal clip applied to hold the foil or wrapper against the hair.

By the expression intrathermal heater, as applied in this application and in reference to hair waving apparatus referred to herein, is meant an interior heating device, the heat effect of which is developed by exothermic material.

According to these prior methods of procedure there is nothing to properly confine the hair on the side of the mandrel toward the head, or to prevent the escape of steam. This allows about one-fourth of the hair of each coil to sag or form a pouch between the mandrel and clamp so that the curls are not of the desired evenness. The formation of the curl near the scalp is also not as good as the formation of the other curls, for this part of the hair has received merely a steam vapor and has not been properly confined so that it slackens instead of being kept under tension.

According to the present invention the wrapper and scalp protector are simultaneously clamped together in such a way that the entire periphery of the wound coil of hair is held taut close down to the scalp and without any possibility of improper stretch.

In the permanent waving art it has been customary to employ scalp protectors, clamps and winding mandrels, and in some instances wrappers and absorbent pads, which were capable of repeated use. These become very unsanitary as the lotions used, cut hair, salts, creams, dirt off the floor and germs readily adhere. These de-

vices are passed from the head of one customer to the head of another customer without any effort to sterilize the same.

The present invention contemplates the provision of hair waving assemblages for permanent waving either by the electric heating, steam heating, or the machineless methods wherein all parts are made so inexpensively that they can be readily discarded after a single use. The scalp protector is made out of paper and will be so damaged by a single use as not to be reusable. Owing to its cheapness it can be readily discarded. The winding mandrel may be made of wood, papier-mâché, or other light inexpensive material, and thus cheap, so that it can be discarded, or the winding mandrel may be of the chemical type which is self-destructive.

By employing the readily discardable parts the customers may be assured that the hair waving operation is carried out under the most sanitary conditions and that there is a minimum likelihood of transferring infection from one customer to another.

The present invention also contemplates hair waving devices for permanent waving which weigh much less than those customarily used, and in view of the large number used at one time considerably less load is imposed on the head.

Other and further objects will appear as the description proceeds.

The accompanying drawings show, for purposes of illustrating the present invention, several embodiments in which the invention may take form, it being understood that the drawings are illustrative of the invention rather than limiting the same.

In these drawings:

Figure 1 is a perspective view illustrating two of the parts going to make up one form of scalp protector;

Figure 2 is a perspective view illustrating the complete scalp protector and a winding mandrel with the hair partly wound on it;

Figure 3 is a perspective view illustrating a further stage in the operations for machineless waving with external heating pad;

Figure 4 is a perspective view illustrating the assembled scalp protector, wrapper and parts while making a machineless wave;

Figures 5 and 6 are cross sectional views on the lines 5—5 and 6—6, respectively, of Figure 4;

Figure 7 is a cross sectional view similar to Figure 5 showing the parts arranged for machine waving;

Figure 8 is a cross sectional view illustrating

the modified form of construction where an ordinary reusable scalp protector is employed;

Figures 9 and 10 are perspective views of a further modified form of readily disposable scalp protector;

Figure 11 is a perspective view of a further modified form of readily disposable scalp protector;

Figure 12 illustrates the scalp protector of Figure 11 with wound hair ready for making a curl;

Figures 13 and 14 are perspective views of a still further modified form of construction;

Figure 15 is a perspective view of another form of construction showing the parts separated; and

Figure 16 is a perspective view showing them assembled for a waving operation.

The scalp protector shown in Figures 1 to 7 may conveniently be made out of two sheets of paper-like material, one being cut to the shape indicated at 20 in Figure 1, and the other cut to the shape indicated at 21 in Figure 1. The paper piece 20 is preferably made of comparatively smooth cardboard of considerable strength and preferably has an outer coating of moisture proof material such as sodium silicate, shellac, rubber, lacquer, etc. It has doubled and pasted edges, as indicated at 22 and 23, scored so as to fold up away from the body of the paper as will be obvious. This paper sheet is also scored, as indicated at 24 and 25, so that it can be folded as indicated and has a longitudinally extending slit 26 and a laterally extending slit 27 which communicates with the slit 26.

The paper piece 21 is preferably made of paper or other material with high insulating value and is of a size to fit between the scorings 24 and 25 of sheet 20. It has a longitudinally extending slit 29 and laterally extending slit 30 as indicated. The upper surface of the paper piece 20 between scoring line 25 and the flap 22 is coated with suitable adhesive and then the insert 21 is superposed. The flap 31 is then folded over so that the two pieces of paper will be pasted together with the slots in registry.

Prior to this pasting operation clips or cradle forming members 32 may be secured to the flap 31, but where such cradles are not desired, they may be omitted. By forming these clips of bent sheet metal it is possible to have supporting portion 32' lengthwise of the scalp protector so as not to cause any bulging of the wrappers used about the wound hair.

When the device shown in Figures 1 and 2 is to be used, a tress of hair is passed in through the slits 27 and 30 and then spread out in the slits 26 and 29. These operations are facilitated by giving the cuts tapered openings as indicated at 30' and 30''. The hair is then wound around the mandrel 33 which may be made of wood or papier-mâché with corrugated ends 34. The hair is wound tightly and then the mandrel brought down into the cradle formed by clips 32 and then wound tighter. These clips are preferably resilient and are arranged to enter the notches in the wooden mandrel after the fashion of a pawl, as indicated at 35. During the winding any slack of hair is taken up and the protector pressed toward the head.

Where machineless waving is to be employed a chemical pad 36 and a flannel 36' moistened with water or lotion are placed about the wound hair. An impervious wrapper 37 of foil and paper preferably with pieces of flannel or porous paper, as indicated at 38, is pressed down about the wound tress of hair and one end 39 brought closely adjacent the flap 31 and upwardly extending

element 22. The other end 40 of the wrapper passes down inside the upwardly extending element 23 of the scalp protector and the flaps 41, as will be clear from the cross sectional views of Figures 5 and 6. When the flap 41 is pressed down into the position indicated it will push the hair to the left of the slot 29 against the flange 22 as indicated in Figure 5 and will also tighten the wrapper about the wound hair. The operator then places a clamp 43 in the position indicated, so as to securely clamp the wrapper, the upwardly extending elements 22 and 23, and the hair together. This at the same time secures the wrapper very tightly about the hair and secures the scalp protector and wrapper together, so that the head is completely protected against the possibility of escaping steam and the hair is held against any undesired expansion at the bottom of the coil. It will be noted from Figure 4 that the cradles or clips 32 have introduced no bulges to be enclosed in the wrapper and hence the latter may be drawn smooth and tight.

After the completion of the waving operation, the parts are removed in reverse order. In removing the scalp protector it is broken so that it may be readily passed by the hair. This destroys the scalp protector.

Where the above devices are to be used in machine waving the chemical pad is omitted, and a moistened flannel or paper pad substituted, as indicated at 50 in Figure 7. The wrapper 38 and clamp 43 are placed in position in the same way and electric heating clamps 52 applied as shown, or the intrathermal heater inserted into the hole 33 in the mandrel 33a.

By employing the light paper scalp protector with thin sheet metal cradles over the mandrel and a wooden or papier-mâché mandrel, it is possible to very materially reduce the weight of the assemblages used for the waving, and in view of the large number of such assemblages necessary for a complete permanent wave, it is apparent that the load imposed on the head is much less than where the conventional construction is employed.

Where it is desired to have available the complete closure of the heating space in a hair waving apparatus of the type in which the scalp protector is used repeatedly, one can employ a structure such as shown in Figure 8. Here the scalp protector is indicated at 53, the mandrel at 54, the chemical heating pad at 55, the flannel at 55' and the wrapper at 56. The one end of the wrapper may, if desired, be secured under a clamping element 57 carried by the scalp protector, while the other end of the wrapper is passed under a cooperative clamping element 58.

In the arrangement shown in Figures 9 and 10, the scalp protector is made of a piece of cardboard 60 doubled on itself, as indicated, and receiving an insert 61. The cardboard may be coated, if desired. The lower flap 62 has slits 63 and 64 opposite similar slits 65 and 66 on the insert. The upper flap 67 has a similar arrangement of slits and carries upwardly extending hair gripping elements 68 and 69 which function similar to the elements 22 and 23 of Figures 1 to 7.

The scalp protector 70 shown in Figures 11 and 12 is made out of corrugated cardboard. It has longitudinally and laterally extending slits 71 and 72 similar to those above described and the slits 71 receive upwardly extending hair engaging elements 73 and 74. The wrapper 75 may be permanently secured to the scalp protector, if

desired. Such a wrapper may be closed about a tress of hair which has been wound around a mandrel and then folded, as indicated in Figure 12, after which it can be clamped by a clamp as indicated at 76.

The arrangement shown in Figures 13 and 14 contemplates the making of a scalp protector by suitably folding a long narrow piece of cardboard as indicated in these figures. This piece of cardboard has a central body portion 80 with a doubled under and glued element 81 to form a straight edge 81'. It is scored and pasted, as indicated at 82, to provide a flap 83 adapted to overlie the body portion and having a slit 84 to the rear of the edge 81'. The piece of cardboard is also scored at 85 to provide a top flap 86. This upper flap is slitted, as indicated at 87, to receive L-shaped pieces of cardboard 88 and 89, which provide upwardly extending hair engaging members 90 and 91. With this arrangement the tress of hair is passed up by the edge 81' and the flap 83 is folded down, the hair being passed through the slit 84, and then the flap 86 folded over and the hair passed between the members 90 and 91, the parts being then in the position shown in Figure 14.

The arrangements shown in Figures 9 to 14, inclusive, do not show any means for supporting the mandrel. Any of them may have cradles 32 and the associated wrapper 31, if desired.

In the arrangement shown in Figures 15 and 16 a permanent scalp protector 90 made of rubber or felt is provided with a slit 91 to receive the hair. It carries a metal frame 92 provided with an upwardly extending slotted cradle 93 at one end and with a reduced extension 94 at the other end. A flexible rubber wrapper 95 is placed between the member 92 and the rubber pad 90 and they are secured to the scalp protector in any suitable way. A mandrel 96 with threaded end 97 carries a wing nut 98 so that the mandrel can be clamped in place on the cradle. After the hair has been wound and the chemical heating pad (not shown) inserted, the wrapper 95 is brought around the curl as indicated in Figure 16 and is clamped in place by a clamping device comprising a bar 99 and a finger piece 100. The bar 99 has a notch 101 to engage a pin 102 and the finger piece 100 extends over the reduced end 94. With this arrangement it will be noted that the wound hair is clamped in place very securely and there is no opportunity for sagging or loosening of the curl. It is obvious that the construction of Figures 15 and 16 can be used for machine waving in which case the wrapper 95 will be made of foil instead of rubber.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. Hair waving apparatus comprising a scalp protector slotted to receive a tress of hair and normally loosely mounted thereon for displacement from the end towards the root of the hair, a mandrel about which the hair is wound, means for mounting the mandrel on the scalp protector, a wrapper disposed around the wound hair on the mandrel after the hair is partly wound on said mandrel, the edges of the wrapper engaging the protector, and a means securing the ends of the wrapper to clamp the same tightly about the

hair and to the protector and simultaneously to clamp the protector to the hair so as to form a steam-tight joint where the hair enters inside the wrapper.

5 2. Hair waving apparatus comprising a scalp protector slotted to receive a tress of hair having upwardly extending hair gripping elements on opposite sides of the slot, a mandrel about which the hair is wound, a wrapper about the wound hair on the mandrel, the edges of the wrapper engaging the outside of one of said elements and the inside of the other, and a clamp engaging the exposed end of the wrapper and the outside element for securing the ends of the wrapper tightly about the hair and to the protector so as to form a steam-tight joint where the hair enters inside the wrapper.

20 3. A non-reusable assemblage for use in permanently waving the hair comprising a scalp protector made of readily destrucible material suitable for a single use only and having a hair receiving slit extending longitudinally along the protector, the same being open at one end of the protector and closed at a point adjacent the other end of the protector and upwardly extending hair gripping elements along the opposite sides of the slit, a winding mandrel of readily destrucible material about which the tress of hair may be wound and held adjacent the slit, a wrapper adapted to extend about the wound tress of hair and to engage the upwardly extending hair gripping elements, and a fastening member adapted to fit about the ends of the wrapper and the hair gripping elements for clamping the wrapper to the hair gripping elements and the hair gripping elements to the scalp protector, all said parts being inexpensive, substantially sterile when applied and suitable for destruction or discarding after a single use.

25 4. A hair waving assemblage such as claimed in claim 3, wherein the protector has mandrel supporting means attached thereto on one side of the slit.

30 5. A hair waving assemblage such as claimed in claim 3, wherein the protector has a foldable cover element at one side of the slit, said foldable cover element carrying one of the hair gripping elements.

35 6. A hair waving assemblage such as claimed in claim 3, wherein the protector has mandrel supporting means attached thereto on one side of the slit, and a foldable cover element at one side of the slit, said foldable cover element carrying one of the hair gripping elements.

40 7. A hair waving assemblage such as claimed in claim 3, wherein the mandrel comprises a chemical heating element.

45 8. A device for use in waving the hair comprising a hair receiving member having a longitudinally extending opening through which the hair passes said receiving member being loosely mounted for vertical movement along the hair, a mandrel about which the hair is wound, and mandrel supporting means including a mandrel receiving seat and a seat support extending parallel with the opening and a clamp operating simultaneously to secure the mandrel to the receiving member and the receiving member to the hair.

50 9. A hair waving construction comprising a protector assembly, a mandrel and a wrapper, said protector assembly comprising two elements, each of elongated conformation and having longitudinal slots extending from one end of each element to a position adjacent the other end

thereof, the respective elements being mounted one upon the other with their slits in vertical alignment, and having their open ends laterally spaced one from the other and facing in opposing directions, means for supporting a mandrel on the uppermost of said elements, the elements being successively loosely mounted on a strand of hair, the mandrel being wound with the hair from its free end towards the scalp, whereby the elements are moved by the mandrel towards the scalp and the wrapper being of conformation to envelope the mandrel carrying the wound hair, a mandrel support on the uppermost of the elements, and a member for simultaneously clamping the wrapper about the mandrel and the upper element to the hair.

10. A hair waving assemblage such as claimed in claim 3, having sheet metal mandrel supporting means comprising a cradle mounted on an upstanding flat portion attached thereto at each end of the slit, with the flat portions of the supporting element extending lengthwise of the slit, so that the wrapper extending about the wound tress carried on the mandrel in the cradle closes tightly.

11. For use in permanently waving the hair, a scalp protector adapted for a single use and comprising, substantially rigid paper-like elements each being provided with a longitudinal slit ex-

tending from one end thereof to a point adjacent the other end, and superimposed one above the other with their slits in vertical alignment, to receive a tress of hair, the open end of the slit of one element being disposed adjacent the closed end of the slit of the other element, thereby to maintain the tress of hair in vertical alignment and against lateral displacement.

12. A scalp protector, such as claimed in claim 10 11, wherein one of the substantially rigid paper-like elements has upstanding flanges extending along opposite sides of the slits thereof to receive a clamp for securing the protector to the hair.

13. For use in permanently waving the hair, a 15 scalp protector adapted for a single use and comprising, substantially rigid paper-like elements, each being provided with a longitudinal slit extending from one end thereof to a point adjacent the other, and superimposed one above the other with their slits in vertical alignment to receive a tress of hair, the open end of the slit of one element being disposed adjacent the closed end of the slit of the other element, upstanding flanges extending along opposite sides of the slits of one 20 25 of said elements, a mandrel about which the hair is wound, a wrapper about the wound hair, and a clamp pressing the ends of the wrapper and the flanges towards the interposed hair.

EMILE J. YVEN.
